UNITED STATES PATENT OFFICE

2,454,861

MACHINE FOR CUTTING HANDHOLES

Alva Claybourne Coker, San Antonio, Tex.

Application July 23, 1945, Serial No. 606,570

5 Claims. (Cl. 144—136)

1

This invention relates to a machine for cutting hand holes in cases such as commonly employed for holding beverages in bottles.

Heretofore, the operation of producing hand holes in cases has been a comparatively slow operation due primarily to the fact that it has been necessary to reverse the position of the work in order to produce the desired rounded edges at both sides of the opening or hand hole.

An object of the present invention is to greatly simplify the construction of machines for the purpose stated whereby it is especially suited for high speed quantity production.

It is a further object to provide a machine of simple construction, the working parts of which are all accessible readily.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings, the preferred form of the invention has been shown.

In said drawings:

Figure 1 is a top plan view of the machine.

Figure 2 is a view partly in elevation and partly in section as viewed from the right of Figure 1.

Figure 3 is a side elevation of the machine, a portion being in section.

Referring to the figures by characters of reference, 1 designates the main frame of the machine, which can be of any suitable proportions and provides a mounting for a motor 2 adapted to transmit motion through belt and pulley mechanism 3 to a transverse shaft 4 journaled on the frame. Pulleys 5 are secured to shaft 4 adjacent to opposite sides of the frame and serve to transmit motion through belts 6 to oppositely disposed aligned spindles 7 which are also journaled on the frame. These spindles are spaced apart at their inner ends and said ends carry replaceable boring and reaming bits 8 which are oppositely disposed, as shown.

Secured in the frame with the spindles 7 extending between them, are guide rods 9. These rods are parallel and are slidably engaged by the respective ends of a carriage 10 having a central longitudinal opening 11. This carriage is below the level of the routing bits 8 and is adapted to be shifted along the guide rods 9 by a lever 12 fulcrumed between its ends, as at 13 and having

2

a yoke 12' at its upper end which embraces and engages a portion of the carriage so that when the lever is shifted, the carriage is moved therewith. A laterally tiltable pedal 14 is fulcrumed between its ends in the bottom portion of the frame at one end, as shown at 15 and is provided with a centrally located upwardly extending arm 16 having a pivotal and sliding connection 17 with the lower end of lever 12. Thus when one end of the pedal is depressed, the yoke 12' and the carriage are moved in one direction as indicated by broken lines in Figure 2, and when the other end of the pedal is depressed, the movement of the parts is reversed.

Mounted in the carriage so as to rock about a pivotal connection 18, is a jig 19 proportioned to receive the case end or other work to be shaped. This jig has upwardly extending side walls 20, each of which is provided with a slot 21 concentric with the axis of movement of the jig and proportioned to receive one of the routing bits.

From one of the walls 20 there is extended a handle 22 while pivotally connected to the other side of the jig is a frame 23 having a handle 24 adapted to overlie the engaged work and to normally rest close to or in contact with the handle 22 so that both can be grasped by one hand of the operator. The pivotal connection between frame 23 and the jig has been indicated at 25.

In practice, the handle 24 is swung away from the handle 22 so that the work, W thus can be placed in the jig. The distance between the two routing bits is greater than the thickness of the work, so that when the jig and carriage are in their normal or intermediate positions, the work will not be engaged by the rapidly rotating bits. By drawing the handle 24 toward the handle 22 and holding them fixed relative to each other, the frame 23 will bind upon the work and hold it securely in the jig. The two handles are then used for the purpose of rocking the jig and the work carried thereby. Before this is done, however, the pedal 14 is pressed downwardly at one side, thereby causing the work to feed against one of the rotating bits. While it is thus located the work is rocked back and forth with the result that an arcuate slot is thus formed, said slot being of the length permitted by the slot 21 in which the bits work. Thereafter, the other end of the pedal is depressed with the result that the work is fed against the other rapidly rotating bit. Said work is rocked as before and thus the hand hole having both sides rounded and properly finished is thus quickly completed. By bringing the parts to their intermediate positions, releasing the work

and removing it, the machine is promptly prepared to receive another case end or the like to be acted on.

It has been found in practice that a machine such as herein described can be used effectively for producing hand holes at high speed so that production is thus greatly increased with a corresponding saving of time and labor.

What is claimed is:

1. A machine for producing hand holes in case ends, including a frame, coaxial opposed routing bits mounted thereon, the distance between the bits being greater than the thickness of the work to be cut, means for rotating the bits, a carriage 10 slidably mounted on the frame between the bits for movement in a line with the axis of the bits, whereby to shift work carried thereby into engagement with either bit, a substantially vertically disposed lever positioned below the carriage, the lever being fulcrumed intermediate its ends to the frame, a yoke at the upper end of the lever proportioned to embrace and engage the carriage at opposed sides of the carriage, a foot 15 pedal connected intermediate its ends to the lower end of the lever, whereby to swing the lever in either direction about its fulcrum point, a work holding jig tiltably mounted in the carriage and positioned normally to support the work between and out of contact with the respective bits, and means under the control of the operator for 20 rocking the jig relative to the carriage.

2. A machine for producing hand holes in case ends, including a frame, coaxial opposed routing bits mounted thereon, the distance between the bits being greater than the thickness of the work to be cut, means for rotating the bits, a carriage 25 slidably mounted on the frame between the bits for movement in a line with the axis of the bits, whereby to shift work carried thereby into engagement with either bit, a lever fulcrumed to the frame, one end of the lever being proportioned for engagement with the carriage, means under the control of an operator at the other 30 end of the lever, for swinging the lever in either direction about its fulcrum point, a work holding jig tiltably mounted in the carriage and positioned normally to support the work between and out of contact with the respective bits, and means under the control of the operator for 35 rocking the jig relative to the carriage, said means comprising a handle fixedly attached to one side of the jig, and a handle pivotally attached to the opposed side of the jig, for swinging movement into 40 engagement with the first named handle, whereby said handles may additionally comprise means for clamping the work in the jig.

3. A machine for producing hand holes in case ends, including a frame, coaxial opposed routing bits mounted thereon, the distance between the bits being greater than the thickness of the work to be cut, means for rotating the bits, parallel 45 guide rods mounted on the frame in parallel relation to the axis of the bits, a carriage slidably mounted on the guide rods and between the bits, pedal means under the control of an operator for shifting the carriage along the guide rods, whereby to shift work supported by the carriage 50 into engagement with either bit, a work holding jig pivotally mounted on the carriage for swingable movement in a vertical arc perpendicular

to the axis of the bits, and means under the control of the operator for swinging the jig relative to the carriage.

4. A machine for producing hand holes in case 5 ends, including a frame, coaxial opposed routing bits mounted thereon, the distance between the bits being greater than the thickness of the work to be cut, means for rotating the bits, parallel 10 guide rods mounted on the frame in parallel relation to the axis of the bits, a carriage slidably mounted on the guide rods and between the bits, pedal means under the control of an operator for shifting the carriage along the guide rods, whereby to shift work supported by the carriage 15 into engagement with either bit, a work holding jig pivotally mounted on the carriage for swingable movement in a vertical arc perpendicular to the axis of the bits, the jig comprising opposed side walls spaced apart to receive the work, the side walls having opposed arcuate bit-receiving 20 slots concentric with the axis of movement of the jig, a handle fixedly attached to one of the side walls, a clamping frame pivotally connected to the opposed side wall, and a handle on the clamping frame, the latter handle being extended for 25 positioning in close relation to the first named handle upon pivotal movement of the clamping frame, whereby to provide means under the control of a hand of the operator for simultaneously 30 clamping the work in the jig, and rocking the jig in the carriage.

5. A machine for producing hand holes in case 35 ends, including a frame, coaxial opposed routing bits mounted thereon, the distance between the bits being greater than the thickness of the work to be cut, means for rotating the bits, parallel 40 guide rods mounted on the frame below and parallel to the axis of the bits, a carriage extending between the guide rods and slidably mounted thereon, whereby to shift work carried by the carriage into engagement with either bit, a lever positioned below the carriage, fulcrumed to the frame for swingable movement in a vertical arc, means at the upper end of the lever proportioned to embrace and engage the carriage, pedal 45 means connected to the other end of the lever under the control of an operator, a work holding jig pivoted to the carriage for movement in a vertical arc, opposed side walls on the jig, a 50 handle fixedly attached to one side wall, a clamping frame pivoted to the other side wall, and a handle on the clamping frame positioned for engagement with the first named handle upon swinging of the clamping frame, the side walls 55 of the jig having opposed arcuate slots formed therein proportioned to receive the respective bits.
